UNITED STATES PATENT OFFICE.

STANLEY A. FLOWERS, OF PITTSBURGH, PENNSYLVANIA, ASSIGNOR TO PITTSBURGH TINWARE MANUFACTURING COMPANY, OF PITTSBURGH, PENNSYLVANIA, A CORPORATION OF PENNSYLVANIA.

CONSTRUCTION FOR METAL STOOLS, STANDS, AND THE LIKE.

Application filed January 13, 1926. Serial No. 80,892.

The object which I have in view is the provision of a structure of such character which may be inexpensively manufactured of sheet metal, which will be strong and durable, and of an attractive and ornamental appearance.

My invention, although advantageously applicable to many kindred purposes, is especially adapted for bath room stools, fern stands and the like.

In general my structure is of the following character.

The body portion with the legs integral therewith is stamped from sheet metal and bent up into inclosed, preferably circular form and its ends connected together as by interengaging hooked flanges which are clamped together. The top element is provided with a continuous flange which is forced down within the body portion, thus bracing the same from within. The top is also supported on the top edge of the body portion.

The legs, which depend from the body portion are provided with cross-braces, and preferably diverge downwardly. The lower edges of the body portion and the vertical edges of the legs are preferably provided with inturned flanges to add strength.

The adjacent legs are connected by upwardly arched portions which add strength and rigidity to the legs, and this is augmented by the inturned flanges.

I provide a new and improved foot structure.

Other novel features of construction, and also structure and arrangement of parts will appear from the following description.

In the accompanying drawings, wherein I have illustrated the best embodiment of the principles of my invention now known to me, Fig. 1 is a view in perspective of a bath room stand made in accordance with my invention; Fig. 2 is a vertical section of the same; Fig. 3 is a top plan view with the top or seat removed; Fig. 4 is a broken perspective showing the invention embodied in a fern-stand, and Fig. 5 is a broken vertical section thereof.

The following is a detailed description of the drawings.

A is the body portion stamped from sheet metal of preferably about 22 gauge and having formed integrally therewith the depending legs 1. While the body portion A 55 may especially in the smaller sizes be stamped in one piece, I prefer to form it of at least two sections having vertical edges which are provided with rearwardly turned hook flanges 2 which are interlocked and 60 clamped tightly together so as to form a continuous body wall of inclosed shape. While the connected up body may be of any shape I prefer a cylindrical form. The lower edges of the body A and the vertical 65 edges of the legs 1 are provided with inturned flanges 3, the flanges of the legs and of the body being continuous. The flanges impart a substantial appearance to the structure and also add strength and rigidity. 70

It will be noted that the legs decrease in width downwardly and are joined at their upper ends by arches or bows in the lower edge of the body structure. This greatly adds to the strength and rigidity of the legs 75 and distributes the strains and stresses instead of localizing them at the lower edge of the body portion.

The angles of the lower legs are slit upwardly to form the tongues 4 which are bent 80 in horizontally one on top of the other and the three flanges are then pierced to receive the rivet 5 by which the cylindrical rubber foot 6 is attached.

The top B of the stool shown in Figs. 1 85 and 2 is also stamped of sheet metal and has a rounded edge 7 to simulate a wooden seat. The top or seat is preferably slightly depressed to further simulate the conventional wooden seat. The top is also provided with 90 a continuous depending flange 8 which is thrust down within the body portion A, thus bracing it outwardly and holding it against any tendency to collapse. The top and its load are supported by resting on the 95 top edge of the body portion, as best shown in Fig. 2.

The legs preferably diverge downwardly.

from the body portion and are connected together and braced in position by the metal cross-braces 9 whose ends are bent at an angle and riveted as at 10 or otherwise attached to the legs.

In forming the body sections the legs 1 are preferably bent longitudinally to form the central angle 11 which adds to their strength and ability to resist lateral strains and thrusts.

The ends of the sections of the body portion A may be welded or otherwise connected but I find that the interlocked hook flanges are satisfactory.

15 In the fern-stand embodiment illustrated in Figs. 4 and 5, the top B' is of pan or sunken form, the side wall 12 of the pan forming the flange which is introduced down in the body portion and braces the same outwardly. The top of the body portion A in this case is provided with an outwardly extending flange 13 and the top B' is also provided with an outwardly extending flange 14 and said flanges are down and in-turned and interlocked and clamped together, as shown in Fig. 5, thus attaching the top B' to the body A and supporting it in place thereon.

30 The stool or stand is enameled or painted in a suitable color, for instance white.

The structure presents a very pleasing and ornamental appearance. It is of great strength and rigidity and therefore durable. It is of inexpensive construction, making a 35 cheaper but better article than a corresponding stool or stand made of wood.

What I desire to claim is:—

1. A sheet metal construction of the character described comprising the combination 40 of a body formed of a plurality of sections bent and having their ends connected together to form an inclosure and said sections being provided with depending legs, and a top supported on said body and having a flange which fits down into the body and braces the same from within, the lower edges of said sections and the vertical edges of the legs being provided with in-turned 45 strengthening flanges, the flanges on the lower edges of the sections and those on the adjacent legs being continuous.

2. A sheet metal construction of the character described comprising the combination 55 of a body portion bent and its edges secured together to form an inclosure and having integral legs depending from the body portion, the tops of said legs being connected by arched portions of the lower edge of the body portion, the sides of the legs and the 60 adjacent arched portions being provided with continuous and in-turned flanges, and a top portion supported on said body portion and provided with a flange which is inserted within the body portion and braces the same 65 from within.

3. A sheet metal construction of the character described comprising the combination of a body portion bent and its edges secured together to form an inclosure and having integral legs depending from the body portion tapering downwardly in width, the tops 70 of said legs being connected by arched portions of the lower edge of the body portion, the sides of the legs and the adjacent arched portions being provided with continuous and in-turned flanges, and a top portion supported on said body portion and provided with a flange which is inserted within the body portion and braces the same from 75 within.

4. An all-metal construction for a stand, stool and the like comprising a body member formed of sheet metal bent up and secured in inclosed form and having legs depending therefrom and integral therewith, 80 and a top member formed of sheet metal having a depending perimetral surface which fits tightly down within the inclosure of the body member and braces the wall of the latter in shape from within.

5. An all-metal construction for a stand, stool and the like comprising a body member formed of sheet metal bent up and secured in inclosed form and having legs depending therefrom and integral therewith, 85 and a top member formed of sheet metal resting on the top of said body member and provided with a depending perimetral surface which fits tightly down within the inclosure of the body member and braces the 90 wall of the latter in shape from within.

6. An all-metal construction for a stand and the like comprising a body member formed of sheet metal bent up and secured in enclosed form and having legs depending 105 therefrom and integral therewith, and a sunken metal pan fitting tightly down within the enclosure of the body member and bracing the latter in shape, the top of the pan being provided with an outwardly extending flange which bears upon the top of the body member.

7. An all-metal construction for a stand and the like comprising a body member formed of sheet metal bent up and secured 115 in enclosed form and having legs depending therefrom and integral therewith, the top of the body member being provided with an outwardly extending flange, and a sunken metal pan fitting tightly down within the enclosure of the body member and bracing the latter in shape from within, the top of the pan being provided with an outwardly extending flange which is superimposed upon 120 the flange of the body member.

8. An all-metal construction for a stand and the like comprising a body member formed of sheet metal bent up and secured in enclosed form and having legs depending 125 therefrom and integral therewith, the top of

the body member being provided with an outwardly extending flange, and a sunken metal pan fitting tightly down within the enclosure of the body member and bracing
5 the latter in shape from within, the top of the pan being provided with an outwardly extending flange which is superimposed

upon the flange of the body member and the flange of the pan being interlocked with the flange of the body member.

Signed at Pittsburgh, Pa., this 30th day
of December, 1925.
